UNITED STATES PATENT OFFICE.

HARVEY LILLIE, OF BELLWOOD, NEBRASKA.

LOADING AND UNLOADING WAGON-BODIES.

SPECIFICATION forming part of Letters Patent No. 430,662, dated June 24, 1890.

Application filed February 7, 1890. Serial No. 339,509. (No model.)

To all whom it may concern:

Be it known that I, HARVEY LILLIE, a citizen of the United States, residing at Bellwood, in the county of Butler and State of Nebraska, have invented a new and useful Device for Hoisting and Unloading Wagon-Bodies, of which the following is a specification.

This invention relates to devices for hoisting and unloading wagon-bodies; and it has for its object to construct a device of this class which shall be simple and easily arranged in position for operation, and by means of which wagon-bodies loaded with loose material of any kind—such as grain—may be conveniently elevated and their contents dumped or discharged into suitable receptacles alongside of which the hoisting apparatus has been placed for operation.

The invention consists in the improved construction, arrangement, and combination of parts which will be hereinafter fully described, and particularly pointed out in the claims.

In the drawings hereto annexed, Figure 1 is a perspective view of my improved hoisting apparatus, showing a wagon in position for having its bed hoisted. Fig. 2 is a perspective view showing the wagon-bed hoisted and in position for dumping or discharging the load. Fig. 3 is a vertical transverse sectional view of the frame. Fig. 4 is a detail view showing the construction of the adjustable portion of the frame. Fig. 5 is a detail view showing the construction of the end-gate 35 of the wagon adapted to be used in connection with my invention.

Like numerals of reference indicate like parts in all the figures.

11 designate a pair of longitudinally-arranged parallel sills, at the corners of which uprights 22 are secured vertically. The upper ends of said uprights are connected by longitudinal frame-pieces 33 and transverse cross-bars 44, and the said uprights are additionally connected by the cross-bars 55.

6 designates the cap-beam, which is connected by inclined braces 7 with the frame-pieces 33 and transverse cross-bars 44. The frame thus constructed is to be of such dimensions as to enable a wagon to be driven between the sides thereof, and the height of said frame is to be limited only by the height

to which it may be desired to hoist the material which is to be unloaded.

88 designate a pair of longitudinal supporting-beams, which are connected adjustably to the corner-posts 2 of the frame by means of clips or clamps 9, encircling the said corner-posts, and having clamping-plates 10, which may be secured by means of the 55 thumb-nuts 11. The supporting-beams 88 are provided with centrally-located downwardly-extending brackets 12, which are connected adjustably with uprights 13, rising from the sills, by means of bolts 14, adapted 60 to be passed through aligned perforations 15 in the said uprights and brackets.

Suitably secured to the under side of the cap-beam 6 are the hooks 16 and 17, to the former of which one end of the hoisting-rope 70 18 is attached. Said hoisting-rope is reeved through pulley-blocks 19 and 20, which are attached, respectively, to the hook 17 and to the hoisting-chains 21, which are adapted to be suitably connected with the wagon-bed 22, 75 which may thus be lifted off the running-gear by means of the hoisting mechanism. The free end of the hoisting-rope 18 is passed under a suitably-arranged guide-pulley 23 and has a whiffletree 24 attached thereto for 80 the attachment of the team.

The wagon-bed 22 is provided with an end-gate 25, which is hinged upon a transverse rod 26. The said end-gate is provided near its lower edge with a cleat 27, having a perforation 28, which is in alignment with a perforation in the bottom of the wagon-bed, as shown at 29. A key or pin 30 may be passed through the perforations 28 and 29 to secure the end-gate in a locked position. The upper 90 end of the key or pin 30 terminates in a ring 31, to which is attached the end of a rope 32, which passes through a guide ring or staple 33 upon the upper edge of the end-gate. Upon a ring 35 at the outer end of the rod 26 95 is attached a hook 36, which is secured at the end of a rope or cord 37. Said rope has an additional hook 38 attached thereto and adapted to engage a ring 39, formed at the outer end of the transverse binding-rod 40 100 at the front end of the wagon-bed.

The operation of the invention is as follows: The hoisting-frame is arranged alongside the bin or grainery into which material is to be

discharged. The wagon is driven in between the sides of the upright frame, and the wagon-bed is connected to the chains, which are attached to the hoisting-rope 18. The team is then transferred from the wagon to the draft attachment at the end of the hoisting-rope, and the wagon-bed, which may be held stable while being hoisted by means of the rope 37, is hoisted until it is slightly above the supporting-beams 8, which have been previously adjusted to the desired height. The wagon-bed is now swung around a one-quarter turn and lowered until it rests upon the supporting-beams 8. The rope 32 is now manipulated to detach the key or pin 30 from the perforation in the end-gate and in the bottom of the wagon-bed, and the said end-gate will now swing out and permit the contents of the wagon-body to be discharged over a chute 41, which has been suitably attached to the supporting-beam 8. This may be readily accomplished by simply hooking or attaching the end of the rope 32 to any suitable point of the frame—for instance, to a cleat 52 upon one of the sills—and slightly hoisting the wagon-body, the rear or tail end of which will thus be held steady, while its front end will be elevated, causing its contents to be quickly discharged.

It will be seen that by the construction of the frame as herein described the supporting-beams upon which the wagon-body rests while its contents is being discharged may be easily and quickly adjusted to the height of the bin into which material is to be discharged; also, that the props which support the central portions of said beams will serve to relieve excessive strain upon the clips or clamping devices by means of which the said supporting-beams are secured to the uprights of the frame.

The general construction of the device is simple and inexpensive, and by its use wagons may be easily and quickly unloaded without spilling any of the contents.

Having thus described my invention, what I claim is—

1. In a hoisting and unloading device, the combination of the frame having the uprights at the four corners thereof, the longitudinal parallel supporting-beams secured

vertically and adjustably to the said uprights, and suitable hoisting mechanism, substantially as set forth.

2. The combination of the frame having the uprights at the four corners thereof, the longitudinal parallel supporting-beams secured vertically adjustable to said uprights, and the adjustable props supporting the central portions of said supporting-beams, substantially as set forth.

3. The combination of the frame having the uprights at the four corners thereof, the longitudinal supporting-beams, the clips serving to secure the said supporting-beams adjustably to the corner-posts, the brackets 12, extending downwardly from said supporting-beams, the uprights 13, mounted upon the sills of the frame, and the connecting-bolts, substantially as set forth.

4. The combination of the frame having the vertically-adjustable supporting-beams, the hoisting-gear, and a rope having hooks, whereby it may be connected detachably to the transverse rods at the front and rear ends of a wagon-bed having a hinged end-gate, substantially as set forth.

5. The combination of the frame having the vertically-adjustable supporting-beams, the hoisting-gear, the guide-pulley for the latter, a chute adapted to be secured to one of the longitudinal supporting-beams, a wagon-body having a hinged end-gate provided with a cleat at its lower edge, a key or pin adapted to pass through a perforation in said cleat and through a corresponding perforation in the bottom of the wagon-bed, and a rope attached to said key and passing through a guide ring or staple upon the upper edge of the end-gate, the free end of said rope being adapted to be secured to a fixed point of the frame for the purpose of securing the wagon-body in position for being tilted, substantially as set forth.

In testimony that I claim the foregoing as my own I have hereto affixed my signature in presence of two witnesses.

HARVEY LILLIE.
